UNITED STATES PATENT OFFICE.

JESSE C. SIMMONS, OF SHELBY, MICHIGAN.

BURNER FOR LIQUID FUEL.

1,091,169.

Specification of Letters Patent. Patented Mar. 24, 1914.

Application filed February 24, 1913. Serial No. 750,276.

To all whom it may concern:

Be it known that I, JESSE C. SIMMONS, a citizen of the United States, residing at Shelby, Michigan, have invented certain new and useful Improvements in Burners for Liquid Fuel, of which the following is a specification.

This invention relates to improvements in burners for burning hydrocarbon fuel, such as kerosene, crude oil, or the like, the same being especially well adapted to the burning of kerosene.

The objects of the invention are: First, to provide an efficient burner of large capacity. Second, to provide in conjunction with such a burner, an improved generator, which will not be liable to clog and which will effectively deliver gas to the burner. Third, to provide in a generator and burner of this kind an efficient device for avoiding the waste and for insuring control of the delivery of the liquid fuel thereto. Fourth, to provide in conjunction with such a burner, an improved pilot arrangement.

Further objects, and objects relating to details and to economies of construction and operation will definitely appear from the detailed description to follow.

I accomplish the objects of my invention by the devices and means described in the following specification.

The invention is clearly described and pointed out in the claims.

A structure constituting a preferred embodiment of my invention is clearly illustrated in the accompanying drawings, forming a part of this specification, in which:

Figure I is a plan view of a burner embodying my improvements, a part of the delivery pipe being broken away. Fig. II is a detail sectional elevation view taken on the irregular line 2—2 of Fig. I, showing the disposition of the various burner parts, and the arrangement of the pilot and the generator and feed pipe. Fig. III is an enlarged detail plan view of the feed pipe delivering to the generator, and adjacent parts, the same being enlarged from the left hand portion of Fig. I. Fig. IV is an enlarged detail sectional elevation view, portions being

shown in full lines, taken on a line corresponding to line 4—4 of Fig. I and Fig. III. Fig. V is an enlarged detail elevation view, taken on a line corresponding to line 5—5 of Figs. I and VI showing details

and arrangement of the generator, and the window for inspection of the pilot and for introduction of the starting torch. Fig. VI is an enlarged detail sectional elevation view taken on line 6—6 of Fig. I, showing details 60 of the irregular gas passage from the generator to the burner nozzles and mixing tube of the main burner and the valve to the pilot burner. Fig. VII is an enlarged detail perspective view of the gas delivery pipe and 65 mixing tube and pilot, as the same would appear when detached and removed from the other assembled parts. Fig. VIII is an enlarged detail sectional elevation view, the parts being shown in full lines, taken on a 70 line corresponding to line 8—8 of Figs. I and VI. Fig. IX is an enlarged detail cross section through the generator, taken on line 9—9 of Fig. VI.

In the drawing, the sectional views are 75 taken looking in the direction of the little arrows at the ends of the section lines, and similar numerals of reference refer to similar parts throughout the several views.

Considering the numbered parts of the 80 drawing, the main burner case 1 is provided with a double bottom structure, the upper portion 2 of which is corrugated and slotted to form the burner head, as clearly appears in Figs. I and II. The generator 3 for the 85 main burner is a flat tube extending above the burner head and is supplied with fuel by the curved feed pipe 4, which extends into the burner above the burner head to be heated, preferably to about 200° Fahrenheit, so that the fuel or oil will be thoroughly warmed before it is delivered into the generator, thereby reducing the proportions of the generator.

The heating tube 4 delivers through the 95 upwardly-projecting loop 5 downwardly to a T-connection 6, past the needle valve into the generator tube 3, as clearly appears in Figs. III and IV. The screw threaded needle valve 7 is provided with a needle point 100 8 fitting into the valve seat 8', and the valve is controlled by the little handle 9 projecting laterally from the same. A suitable stuffing box 10 is provided, as also clearly appears in Fig. IV.

The generator tube 3 is horizontal and preferably flat in cross section, as clearly appears in Figs. II, VIII and IX, the pilot generator 17 being arranged directly beneath the same and being of much smaller 110

dimensions, though of similar cross section. The generator tube 3 delivers upwardly into the upright passage 11 in the head block 12 to the transverse feed connection or passage 13, which delivers laterally and downwardly through the downwardly delivering tubes or pipes 14, to the main burner nozzles 15—15 at each side. These nozzles 15—15 each deliver a jet under strong pressure into the mixing tubes 16, 16 of the main burner. These mixing tubes 16, 16 fit tight into the burner casing and extend well toward the center thereof so that the fuel mixture will be delivered out under the burner head plate 15 and be delivered up evenly through all the slits of the burner.

I desire to remark that a burner with a single mixing tube is, of course, entirely available in this behalf, but the large size 20 burner here illustrated is the size usually made use of in a Stanley steamer automobile and is best served by a pair of these mixing tubes. For certain purposes, with a lower pressure, a greater number of tubes 25 might be required. The structure I here show will take care of the fuel delivered by the generator under pressures varying from thirty-five to a hundred pounds. I mention this to show the large capacity and the variations 30 that may be called for by different qualities of fuel. This shows completely the course of the fuel through the main burner and its generator. It will be noted that the fuel is delivered through the connection to the feed pipe 4, then passes up through the loop 5, and owing to the fact that this loop projects upwardly, the fuel will be trapped and retained in the heating tube, and will only be delivered into the generator as it is 35 needed and as it can be effectively and completely generated. So that there is no likelihood of anything but pure gas passing from the generator, I form the passage from the generator up and then laterally and 40 down to the nozzles which deliver to the mixing tubes.

By making the generating tube flat and heating the same to a comparatively high temperature above the burner, the fuel is 50 at once distributed in a thin layer so that it is all completely evaporated and I have never found any deposit of any kind in this generator after many months of use. In order to make a burner of this kind effective, it must be provided with an effective 55 pilot burner for controlling the same, and enabling the temperature to be kept up. The small amount of fuel necessary to generate for the pilot is taken care of by a small 60 flat generator tube 17 disposed directly beneath the main generator tube 3. This is supplied with fuel through the upwardly-projecting coupling 17', which retains the fuel and prevents its delivery except when 65 needed in the generator, enabling the gas

pressure to retard the entrance of the fuel. This pilot generator has an upwardly extending delivery passage 18 delivering laterally at 19 and downwardly at 20 and through the lateral passage 21, and downwardly at 22 to the pilot burner valve, which is a valve casing 23 having a screw threaded valve 24 with a needle point 25 for controlling the delivery of the fuel into the mixing tube 26 leading into the pilot burner 27, 70 which is a rectangular tubular case suitably slotted at the top, the relation of which clearly appears on an inspection of Figs. II, VI and VII.

Observation shows that a small pilot generator, such as here illustrated, will be destroyed by the intense heat unless protected. The main and pilot generator tubes must be intimately connected so that the pilot tube will be cooled from contact with the 80 main generator tube, or destruction will occur, as above stated. This is effected by brazing the two tubes integrally of the same metal.

A tubular enlargement 29 surrounds the 90 valve casing 23 for the delivery of air to the pilot mixing tube 26. The outer casing 28 extends from this enlarged tube 29 and embraces the same, and a pivoted window 30, with a mica pane 31, is supported on the 95 housing or casing 28 to permit inspection of the condition of the pilot and also to permit the introduction of the generator torch at this point.

From this description it will be observed 100 that when the burner is in commission, the pilot is always in operation and consequently any slight amount of fuel that passes through the same will be generated and used up and it is not necessary to absolutely protect the pilot generator tube from the delivery of fuel when the burner is not in operation. The pilot generator, however, should prevent the possible delivery of any liquid fuel therefrom, and this is taken care of by 105 the upwardly-extending passage 18 therefrom, as has been described.

From the description of the parts above given, the operation of the structure will be 110 very readily understood. In the burner as 115 I have made use of it, the liquid fuel has been delivered under comparatively high pressure, varying from thirty-five to a hundred pounds by the usual pressure means supplied on an automobile, like the Stanley 120 automobile, for instance, and the parts I have here shown are of the proportions of such parts, the main burner illustrated in Fig. I being eighteen inches in diameter. The pilot burner supply and the main burner 125 supply are connected to the same pressure tank. The usual torch is introduced through the window 30, and the pilot is then started after the generation begins. This immediately heats up the main generator tube, and 130

after two or three minutes operation of the pilot the full burner is ready to start. The full burner, as soon as it is heated, works with full capacity and will generate steam in the usual automobile boiler in from three to five minutes, depending upon the adjustment of the burner.

By the arrangement of the burner, I avoid all accumulations of carbon, so far as I have 10 been able to detect the same, and have provided a burner in which it is unnecessary to introduce any special cleaning devices because for use with such hydrocarbon fuel, as kerosene, the operation of the burner is 15 so efficient that there is no opportunity for accumulations of any kind whatsoever.

The substantially horizontal flat pipe immediately causes the distribution of the liquid fuel and prevents its boiling in contact 20 with the heated surfaces, which is the thing that induces the deposit of carbon and accumulations which clog the burner. The fuel does not have time to rest in contact with the metal but immediately passes forward 25 and is completely vaporized in the heated pipe without standing in contact with the metal of the pipe. This is my understanding of the operation of the device, and it certainly avoids any deposit of carbon, as I 30 am aware from an extensive test of the burner under severe conditions.

My improved burner is here shown adapted to automobile use, and especially to an automobile burner.

35 The invention is applicable to any kind or style of a tubular or flat topped burner, and I do not wish to be understood as restricting my broader claims to the particular form of burner which I have here illustrated, as 40 any form can be made use of in this behalf. A sawed burner, or a bored burner is equally available.

The particular arrangement of the parts I have here shown is especially effective and 45 I desire to claim the same specifically, as well as broadly as indicated by the appended claims.

The loop for warming the fuel is of especial advantage, but I know from experience 50 that it can be dispensed with.

Having thus described my invention, what I claim as new and desire to secure by Letters Patent is:

1. In a burner structure, the combination 55 of a burner head for delivering jets of flame, a mixer tube means delivering into the said burner head, a horizontal generator tube disposed above the said burner head that is flat in cross section presenting a broad horizontal surface for reception of the liquid fuel, a fuel delivery pipe connected to said generator, having a portion disposed in the heat zone of the said burner for warming the liquid fuel and an upwardly looped portion before its connection to the generator,

a head with a passage extending upwardly and thence leading downwardly from said generator, a burner nozzle at the end thereof for the delivery of the generated gas to the mixer tube means leading into the said 70 burner head, a pilot burner having a mixing tube, a smaller flat horizontal generator tube for the pilot burner disposed beneath the main generator and intimately connected thereto, an upwardly and thence downwardly extending passage from said pilot generator extending above the main burner head and thence downwardly to a point below the level of the pilot generator, all coacting substantially as described for the purpose specified.

2. In a burner structure, the combination of a burner head for delivering jets of flame, a mixer tube means delivering into the said burner head, a horizontal generator tube disposed above the said burner head that is flat in cross section presenting a broad horizontal surface for reception of the liquid fuel, a fuel delivery pipe connected to said generator having a portion disposed in the heat zone of the said burner for warming the liquid fuel and an upwardly looped portion before its connection to the generator, a head with a passage extending upwardly and thence leading downwardly from said generator, and a burner nozzle at the end thereof for the delivery of the generated gas to the mixer tube means leading into the said burner head, all coacting substantially as described for the purpose specified.

3. In a burner structure, the combination of a burner head, a horizontal generator tube disposed above the said burner head that is flat in cross section presenting a broad horizontal surface for reception of the liquid fuel, a fuel delivery pipe connected to said generator having an upwardly looped portion before its connection to the generator, a head with a passage extending upwardly and thence leading downwardly from said generator, a burner nozzle at the end thereof for the delivery of the generated gas to the burner head, a pilot burner, a smaller flat horizontal generator tube for the 105 pilot burner disposed beneath the main generator and intimately connected thereto, an upwardly and thence downwardly extending passage from said pilot generator in said head, and suitable connections from said 110 pilot generator extending above the main burner head and thence downwardly to a point below the level of the pilot generator, all coacting substantially as described for the purpose specified.

4. In a burner structure, the combination of a burner head, a horizontal generator tube disposed above the said burner head that is flat in cross section presenting a broad horizontal surface for reception of the 130

liquid fuel, a fuel delivery pipe connected to said generator having an upwardly looped portion before its connection to the generator, a head with a passage extending upwardly and thence leading downwardly from said generator, and a burner nozzle at the end thereof for the delivery of the generated gas to the burner head, all coacting substantially as described for the purpose specified.

5. In a burner structure, the combination of a burner head, a horizontal generator tube disposed above the said burner head that is flat in cross section presenting a broad horizontal surface for reception of the liquid fuel, a pilot burner, a smaller flat horizontal generator tube for the pilot burner disposed beneath the main generator and intimately connected thereto, an upwardly and thence 15 downwardly extending passage from said pilot generator in said burner head, and suitable connections from said pilot generator extending above the main burner head and thence downwardly to a point below the 20 level of the pilot generator, all coacting sub- 25

stantially as described for the purpose specified.

6. In a burner structure, the combination with the burner head, of a straight horizontal generator tube disposed above the burner head, flat in cross section, and with an upwardly extending delivery passage extending thence downwardly to the burner head, as specified.

7. In a burner structure, the combination with the burner head, of a horizontal generator tube, flat in cross section, disposed above the burner head, a pilot burner, and a flat horizontal pilot generator tube beneath the main generator, intimately associated therewith and above the said burner head, as specified.

In witness whereof, I have hereunto set my hand and seal in the presence of two witnesses.

JESSE C. SIMMONS. [L. S.]
